CLAIM

We claim the ornamental design for a pet chew, as shown and described.

DESCRIPTION

FIG. 1 is a perspective view of a pet chew illustrating a new design.

FIG. 2 is another perspective view of the pet chew shown in FIG. 1.

FIG. 3 is front elevation view of the pet chew shown in FIG. 1.

FIG. 4 is a rear elevation view of the pet chew shown in FIG. 1.

FIG. 5 is a top plan view of the pet chew shown in FIG. 1.

FIG. 6 is a bottom plan view of the pet chew shown in FIG. 1.

FIG. 7 is a side elevation view of the pet chew shown in FIG. 1.

FIG. 8 is another side elevation view of the pet chew that is opposite the side elevation view shown in FIG. 7.

FIG. 9 is a perspective view of a pet chew illustrating another new design.

FIG. 10 is another perspective view of the pet chew shown in FIG. 9.

FIG. 11 is a front elevation view of the pet chew shown in FIG. 9.

FIG. 12 is a rear elevation view of the pet chew shown in FIG. 9.

FIG. 13 is a top plan view of the pet chew shown in FIG. 9.

FIG. 14 is a bottom plan view of the pet chew shown in FIG. 9.

FIG. 15 is a side elevation view of the pet chew shown in FIG. 9.

FIG. 16 is another side elevation view of the pet chew that is opposite the side elevation view shown in FIG. 15.

FIG. 17 is a perspective view of a pet chew illustrating a further new design.

FIG. 18 is another perspective view of the pet chew shown in FIG. 17.

FIG. 19 is a front elevation view of the pet chew shown in FIG. 17.

FIG. 20 is a rear elevation view of the pet chew shown in FIG. 17.

FIG. 21 is a top plan view of the pet chew shown in FIG. 17.

FIG. 22 is a bottom plan view of the pet chew shown in FIG. 17.

FIG. 23 is a side elevation view of the pet chew shown in FIG. 17.

FIG. 24 is another side elevation view of the pet chew that is opposite the side elevation view shown in FIG. 23.

FIG. 25 is a perspective view of a pet chew illustrating yet another new design.

FIG. 26 is another perspective view of the pet chew shown in FIG. 25.

FIG. 27 is a front elevation view of the pet chew shown in FIG. 25.

FIG. 28 is a rear elevation view of the pet chew shown in FIG. 25.

FIG. 29 is a top plan view of the pet chew shown in FIG. 25.

FIG. 30 is a bottom plan view of the pet chew shown in FIG. 25.

FIG. 31 is a side elevation view of the pet chew shown in FIG. 25; and,

FIG. 32 is another side elevation view of the pet chew that is opposite the side elevation view shown in FIG. 31.

Shade lines shown in the accompanying drawings represent surface contour only and not texture, color, shading, or surface ornamentation.

The broken lines in the drawings illustrate portions of the pet chew which form no part of the claimed design.
